CONCEALED HINGE

Joseph Soss, Roselle, N. J.

Application July 9, 1940, Serial No. 344,475

13 Claims. (Cl. 16—166)

This invention relates to concealed hinges of the type and kind employing superimposed links pivoted to each other and to the housing butt parts at one end, and having sliding connections at the other ends with opposed housing butt parts; and the object of my invention is to provide housing butt parts of the class described formed from sheet material so shaped as to form the various bearings or guide channels of the casing portion, and further so as to reinforce and strengthen said butt parts while materially reducing the cost thereof as well as the weight of said parts, and still further in providing longer wearing bearing surfaces; and with these and other objects in view, the invention consists in a hinge of the class and for the purpose specified, which is simple in construction, efficient in use, and which is constructed as hereinafter described and claimed.

20 The invention is fully disclosed in the following specification, of which the accompanying drawing forms a part, in which the separate parts of my improvement are designated by reference characters in each of the views, and in which:

25 Fig. 1 is a side view of a hinge made according to my invention with the butts in closed position and with part of the construction in section.

Fig. 2 is a plan and sectional view substantially on the line 2—2 of Fig. 1.

30 Fig. 3 is a partial section on the line 3—3 of Fig. 2.

Fig. 4 is a sectional plan view of the hinge with the parts in open position.

Fig. 5 is an exploded perspective view showing 35 the separate parts of one butt in position for assembly; and

Fig. 6 is a view similar to Fig. 5 showing a modified form of butt structure.

In the manufacture of concealed multiple link 40 hinges wherein each link is composed of a single metallic body or laminated body, it has been the customary procedure to provide housing butt parts usually formed from die castings. This type of hinge has been found objectionable primarily from the standpoint of the cost of producing the same and also from the standpoint of the weight of the hinge and the wearing properties thereof. It is the purpose of my invention to construct housing butt parts of hinges of the 45 type and kind under consideration from sheet metal first to materially reduce the cost of these butts; secondly, to lighten the weight thereof; and thirdly, to produce a stronger butt and one of longer life wear. Still further, in constructing 50 hinge butts of the character described from sheet

metal, the shaping of the sheet metal to form the various guides and bearings, automatically produces in the resulting butt a very strong and sturdy reinforced butt.

In illustrating one adaptation of the invention, I have shown in Figs. 1 to 5 inclusive a concealed hinge comprising two housing butt parts 10, 10a, each of which is of the same construction, and simply reversed as to position in coupling the two butts together by a series of links 11, 11a. 5 The links 11 are fixedly pivoted to the butt 10 as at 12, whereas the links 11a are fixedly pivoted to the butt 10a as at 12a. The links 11 also have sliding pivotal mountings 13 in the butt 10, whereas the links 11a have sliding pivotal mountings 13a in the butt 10a. The links are of the general contour illustrated in plan in Figs. 2 and 4 of the drawing and are pivotally coupled to each other centrally thereof as seen at 14. This link construction is more or less conventional. It will 20 also appear that on the sliding pivot pins 13, sleeves 15 are disposed to provide free sliding movement of the pins in channels or guides in the butt 10a, and similar sleeves 15a are employed on the pivot pins 13a.

25 Each butt 10, 10a, is composed of two sheet metal parts; and as both butts are of identical form, the brief description of one will apply to the other. It will be understood that the butt 10a is simply reversed to dispose the parts which 30 are shown on the bottom in the butt 10 in Fig. 5, as being on the top in the butt 10a. One part of each butt comprises a housing or box-shaped part 16 having spaced horizontal bearing walls 17, and 18, joined at one side in a vertical wall 19, and the front edges of the walls 17 and 18 include laterally extending attaching plate flanges 20, 21. Both horizontal walls 17 and 18 are pressed outwardly to form forwardly and 35 backwardly extending grooves or channels 22 and 23, respectively, which terminate short of the flanges 20, 21. As will be apparent, these channels form reinforcing ribs which extend substantially the full length of the walls 17 and 18.

The walls 17 and 18 are apertured as seen at 40 45 24 to receive the pivots 12, 12a. It will appear from a consideration of Figs. 2, 4 and 5, that the vertical wall 19 is shorter in width than the length of the walls 17 and 18 to form a space 25 at the attaching plate ends of the part 16 to 50 receive spaced cylindrical bearing portions 26 on the companion butt part 16a, which is shown detached from the part 16 in Fig. 5 of the drawing.

The part 16a comprises substantially a cor- 55

rugated strip of metal offset to form two long U-shaped or channeled bearing portions 27, 27a between which is a space or channel 28 for receiving one link of the hinge. Outwardly of the bearing 27 or between this bearing and the wall 17 is formed another space or channel 28a for receiving another link of the hinge. The wall portion 29 of the part 16a which joins the two bearings 27, 27a, has at its outer end one of the cylindrical bearings 26, whereas the wall portion 30 which extends from the bearing 27 includes at its forward end the other of the bearings 26, as will clearly appear in Fig. 5 of the drawing. The wall portions 29 and 30 are arranged directly upon the vertical wall 19 and are welded or otherwise secured thereto so that the part 16a becomes an integral part of the part 16 in forming the complete hinge.

It will also appear from a consideration of Fig. 5 of the drawing that the free side edge of the wall 18 of the part 16 includes an upwardly extending flange portion 31 which forms a bearing member of a width equal to the width of the wall part 19 and adapted to engage or to be arranged in juxtaposition to the adjacent link; for example the lower link 11a, Fig. 1, and the upper link 11, Fig. 2. It will also appear that the outer edges of the horizontal wall portions of the bearings 27, 27a are rounded as seen at 32, note Figs. 2 and 5, to clear the links when the butts are in closed position as seen in Fig. 2.

With the structure as shown in Figs. 1 to 5 inclusive it will be apparent that two relatively simple sheet metal parts can be produced in forming upon the assemblage thereof a strong and durable sheet metal hinge butt, the corrugated formation of the part 16a adding material strength to the butt while at the same time forming the spaced bearings which guide and reinforce the links of the hinge, as well as in forming bearing surfaces over which the bearing sleeves 15, 15a are free to slide. In this connection it will be understood that the vertical surfaces of the bearings 27, 27a are in alinement with the grooves 22, 23, as is clearly seen in Figs. 2 and 3 of the drawing.

In Fig. 6 of the drawing, I have shown for the purpose of illustrating another adaptation of the invention, one butt part made from a single sheet of material rather than from the two sheet metal parts as shown in Fig. 5. Here again, as both butts are of identical form, the brief description of one will apply to both, and for this reason only one butt is shown. The butt part is designated generally by the reference character 33 and comprises substantially similar top and bottom walls 34, joined at one side by a vertical wall portion 35; the forward ends of the walls 34 having laterally extending flanges 36. The walls 34 have outwardly pressed channeled portions 37 which are similar in all respects to the channeled portions 22, 23; the walls 34 having apertures 38 similar to the apertures 24 for receiving the fixed pintles of the links of the hinge similar to the pintles 12, 12a.

At 39 is shown the vertically arranged flanged portion equivalent to the flange 31. With the present construction, instead of using a separate part such as the part 16a, the vertical wall 35 is pressed inwardly to form one channeled bearing 40 similar to the bearing 27, whereas the inwardly set wall portion 41 forms the bearing equivalent to the bearing 27a. This wall extends downwardly into and partially forms the channel 37. With this construction it will ap-

pear that the bottom wall part 34 of the box-shaped housing extends beyond the inwardly set wall 41 as indicated in dotted lines at 34a, and forms the support for the fixed pivot pin of the hinge. The forward edges 42 of the bearings 40, 41, terminate short of the attaching plates 36 of the butt as do the bearings 27, 27a, providing the clearance for the hinged links as will be apparent. The forward edges of the wall 35 or portions thereof above and below the bearing 40 terminate in cylindrical bearings 43 similar to the bearings 26 for receiving the fixed pintle of the hinge. These bearings are in alinement with the apertures 38.

It will be understood that if desired, the entire U-shaped box portion comprising the plates 34, 35 and their associated parts may be contained in a box-shaped shell similar to the parts 17, 18 and 19, simply to form a uniform box-shaped appearance as well as adding somewhat to the strength of the hinge. However, the use of such a housing is not absolutely essential. For this reason, the housing is not indicated. This is also done for sake of clarity in the illustration.

Hinges of the type and kind herein described may be made in slightly different forms of construction and may be produced in many sizes in adapting the same to different uses. It is desirable, however, in the construction of hinges of this kind to keep limits of the hinge within a more or less rectangular box-shaped contour, particularly with respect to the U-shaped housing part which facilitates the mounting of the butts in connection with their supports. It will also be apparent that in some instances, instead of using relatively thick links, links of the laminated construction may be employed. Here again the number of links employed in the respective butts may be varied and the butt structure varied accordingly to suit different types and kinds of installations.

Having fully described my invention, what I claim as new and desire to secure by Letters Patent, is:

1. A concealed hinge of the class described comprising housing butt parts and links pivoted to each other and each fixedly pivoted to one butt part and slidably pivoted to the other butt part in hingedly coupling the same, each housing butt part comprising a sheet metal body having an inner casing part comprising spaced horizontal walls united at one side by a vertical wall, the forward ends of said horizontal walls having laterally extending flanges, the horizontal walls having outwardly extending channels arranged longitudinally thereof to provide bearing grooves for the sliding pivots of the links of the hinge, said horizontal walls having pivot apertures at the forward edges thereof adjacent said vertical wall, and means integral with said vertical wall forming spaced cylindrical bearings registering with said apertures.

2. A concealed hinge of the class described comprising housing butt parts and links pivoted to each other and each fixedly pivoted to one butt part and slidably pivoted to the other butt part in hingedly coupling the same, each housing butt part comprising a sheet metal body having an inner casing part comprising spaced horizontal walls united at one side by a vertical wall, the forward ends of said horizontal walls having laterally extending flanges, the horizontal walls having outwardly extending channels arranged longitudinally thereof to provide bear-

ing grooves for the sliding pivots of the links of the hinge, said horizontal walls having pivot apertures at the forward edges thereof adjacent said vertical wall, means integral with said vertical wall forming spaced cylindrical bearings registering with said apertures, and said vertical wall having an inwardly extending member intermediate opposed inner surfaces of said horizontal walls for spacing a pair of links one 10 from the other.

3. In a concealed hinge of the class described employing substantially similar housing butt parts, each butt part comprising a body of sheet material fashioned to form spaced horizontal walls integrally united at one side by a vertical wall, forward edges of the horizontal walls protruding beyond the forward edge of the vertical wall and terminating in laterally extending attaching flanges, said horizontal walls having 20 outwardly extending elongated ribs forming corresponding guide channels on inner opposed surfaces of said horizontal walls throughout substantially the full length thereof, said horizontal walls having pintle apertures at the forward 25 corners thereof adjacent the vertical wall, and said vertical wall having spaced cylindrical bearings registering with said apertures.

4. In a concealed hinge of the class described employing substantially similar housing butt parts, each butt part comprising a body of sheet material fashioned to form spaced horizontal walls integrally united at one side by a vertical wall, forward edges of the horizontal walls protruding beyond the forward edge of the vertical 30 wall and terminating in laterally extending attaching flanges, said horizontal walls having outwardly extending elongated ribs forming corresponding guide channels on inner opposed surfaces of said horizontal walls throughout substantially the full length thereof, said horizontal walls having pintle apertures at the forward corners thereof adjacent the vertical wall, and one of said horizontal walls having on the other side edge thereof a flange extending in the direction of the other of said horizontal walls.

5. In a concealed hinge of the class described employing substantially similar housing butt parts, each butt part comprising a body of sheet material fashioned to form spaced horizontal walls integrally united at one side by a vertical wall, forward edges of the horizontal walls protruding beyond the forward edge of the vertical wall and terminating in laterally extending attaching flanges, said horizontal walls having 40 outwardly extending elongated ribs forming corresponding guide channels on inner opposed surfaces of said horizontal walls throughout substantially the full length thereof, said horizontal walls having pintle apertures at the forward corners thereof adjacent the vertical wall, said vertical wall having spaced inwardly offset portions forming spacing means for the links of said hinge, and the inner surface of said offset portions being parallel to and in alinement with the guide channels in said horizontal walls.

6. In a concealed hinge of the class described employing substantially similar housing butt parts, each butt part comprising a body of sheet material fashioned to form spaced horizontal walls integrally united at one side by a vertical wall, forward edges of the horizontal walls protruding beyond the forward edge of the vertical wall and terminating in laterally extending attaching flanges, said horizontal walls having 50 outwardly extending elongated ribs forming cor-

responding guide channels on inner opposed surfaces of said horizontal walls throughout substantially the full length thereof, said horizontal walls having pintle apertures at the forward corners thereof adjacent the vertical wall, said 5 vertical wall having spaced inwardly offset portions forming spacing means for the links of said hinge, and the remaining portions of said vertical wall having at the forward edge thereof cylindrical bearings registering with the pintle 10 apertures of said horizontal walls.

7. In a concealed hinge of the class described employing substantially similar housing butt parts, each butt part comprising a body of sheet material fashioned to form spaced horizontal 15 walls integrally united at one side by a vertical wall, forward edges of the horizontal walls protruding beyond the forward edge of the vertical wall and terminating in laterally extending attaching flanges, said horizontal walls having 20 outwardly extending elongated ribs forming corresponding guide channels on inner opposed surfaces of said horizontal walls throughout substantially the full length thereof, said horizontal walls having pintle apertures at the forward 25 corners thereof adjacent the vertical wall, means on said vertical wall forming an inwardly extending bearing and spacing member, the inner surface of which is parallel to said channels, cylindrical pintle bearings at the forward edge 30 of said vertical wall and in alinement with the pintle apertures in said horizontal walls, and the means forming said spacing member and cylindrical bearings comprising an independently fashioned member fixedly secured to said 35 vertical wall.

8. In a concealed hinge employing substantially similar housing butt parts with links having pintles for pivotally and slidably engaging the links with said butt parts in coupling said butts together, each butt comprising a substantially U-shaped sheet metal body having laterally extending flanges at one edge thereof, means on said body forming fixed and slideable pivot mountings for the links of the hinge, an independent sheet 40 metal part fixedly secured to said body and extending into the channel thereof, and means on said part for spacing said links and forming bearings for the pintles of said links.

9. In a concealed hinge employing substantially 50 similar housing butt parts with links having pintles for pivotally and slidably engaging the links with said butt parts in coupling said butts together, each butt comprising a substantially U-shaped sheet metal body having laterally extending 55 flanges at one edge thereof, means on said body forming fixed and slideable pivot mountings for the links of the hinge, an independent sheet metal part fixedly secured to said body and extending into the channel thereof, means on said part for spacing said links and forming bearings for the pintles of said links, said last named means comprising elongated horizontal channeled portions on said part, and vertically arranged cylindrical bearings at one edge thereof.

10. The combination with a sheet metal substantially U-shaped butt housing for link hinges of the class described, of a sheet metal part fixedly secured to said housing, said part having at least one longitudinal channeled portion extending 70 into said butt part forming a link spacing and pintle guiding member, said part including spaced cylindrical pintle bearings at one edge thereof for supporting the fixed pintle of the hinge.

11. A hinge butt for concealed link hinges of the class described, said butt being formed of two parts, one comprising an outer U-shaped body having spaced horizontal walls integrally united at one side by a vertical wall, said horizontal walls having at the forward edge thereof laterally extending attaching flanges, the other part comprising a sheet metal strip having vertically spaced horizontal channeled portions with vertically arranged cylindrical bearings at one edge thereof disposed above and below one of said channeled portions, said second named part being arranged upon and fixedly secured to the inner surface of the vertical wall of the first named part to dispose the channeled portions intermediate the horizontal walls of the first named part and with said cylindrical bearings intermediate and adjacent said attaching plate portions.
12. A hinge butt for concealed link hinges of the class described, said butt being formed of two parts, one comprising an outer U-shaped body having spaced horizontal walls integrally united at one side by a vertical wall, said horizontal walls having at the forward edge thereof laterally extending attaching flanges, the other part com-

prising a sheet metal strip having vertically spaced horizontal channeled portions with vertically arranged cylindrical bearings at one edge thereof disposed above and below one of said channeled portions, said second named part being arranged upon and fixedly secured to the inner surface of the vertical wall of the first named part to dispose the channeled portions intermediate the horizontal walls of the first named part and with said cylindrical bearings intermediate and adjacent said attaching plate portions, and means in addition to said channeled portions and cylindrical bearings forming fixed and slidably mountings of the hinge links in said butt.

13. In concealed link hinges employing U-shaped butt housings, a pintle bearing and guide member for each butt, said member comprising a strip of metal fashioned to form longitudinally spaced and horizontally arranged U-shaped channeled portions forming link and pintle guides and bearings, and one edge of said strip terminating in spaced vertically arranged cylindrical bearings disposed above and below one of said U-shaped channeled portions.

JOSEPH SOSS.
